REVOLVING TOP BUILDING

Filed July 30, 1929

2 Sheets-Sheet 2

UNITED STATES PATENT OFFICE

CHARLES T. RICE AND CHARLES E. CHILDS, OF LUBBOCK, TEXAS; SAID CHILDS
ASSIGNOR TO SAID RICE

REVOLVING-TOP BUILDING

Application filed July 30, 1929. Serial No. 382,129.

This invention relates to buildings such as are used as stands at fairs, carnivals, exhibitions or along the side of a road for the purpose of dispensing cold drinks, food or novelties, and the general object of the invention is to provide a structure of this kind having a revolving top or roof formed with a plurality of faces which may be used for advertising matter, means being provided whereby the roof or top may be rotated at any required speed so as to display the advertising on the top or roof.

Other objects have to do with the details of construction and arrangement of parts whereby this result is accomplished.

Our invention is illustrated in the accompanying drawings, wherein:—

Figure 1 is a front elevation of a stand or booth constructed in accordance with our invention;

Figure 2 is a section on the line 2—2 of Figure 1;

Figure 3 is a fragmentary elevation partly in section showing the central post and the rafters whereby the roof is supported and also showing the driving mechanism for the roof or top;

Figure 4 is a vertical sectional view through one of the rafters, the roof and the side walls and showing the track upon which the roof turns;

Figure 5 is an elevation of the central post;

Figure 6 is a fragmentary view showing the manner in which the motor may be electrically connected to a source of energy.

Referring to these drawings, 10 designates the base of the building which has a concrete footing 11 for the reception of the central mast 12. This mast is preferably made of pipe as, for instance, pipe three inches in diameter, and may extend upward to any desired degree. This pipe below the top of the roof is extended by pipe sections 13 and 14, the pipe section 14 being designed to extend above the revolving top or roof and being provided with a flange 15 of any desired and attractive character.

Extending upward from the base is a wall 16 which may be, and preferably is, formed

of brick, though we do not wish to be limited to this. This wall may extend upward to any desired height as, for instance, a height of four feet, and the wall supports shelving 17 which may be used as a counter. Extending upward from the base 10 or from the wall, as desired, though preferably extending upward from the base and being disposed within the wall are the posts 18 which may be of any desired height. These posts are preferably connected by beams 19 at the top of the posts, though any suitable framing may be used. These beams 19 are bolted to the posts and are disposed outward of the same.

It will be seen that we have shown a building which is octagonal in plan, but we do not wish to be limited to this.

Hingedly connected to the beams 19 so as to swing upward and outward are the doors or shutters 20 which are normally held upward by any suitable bracing or supporting means but which may be swung downward when it is desired to close up the stand. Disposed above the upper faces of the beams 19 is a circular track 21 supported by brackets 22 from the posts 18.

The roof may have any suitable framing, but we have illustrated the downwardly curved or downwardly and outwardly extending rafters 23 which extend upward to the central pipe and downward and outward beyond the beams 19. At intervals upon these rafters are disposed the depending brackets 24 which carry upon them the upper and lower rollers 25 and 26 which engage above and below the track 21 respectively. The upper ends of the rafters are mounted upon a sleeve 27 loosely surrounding the pipe standard 13 and supported by a shoulder 28 welded to the pipe 13. This sleeve 27 is provided with the flange 29, to which the upper ends of the rafters are bolted by bolts 30.

Disposed above the sleeve and welded to the pipe 13 is a beveled gear wheel 31, and mounted upon the roof framing formed by the rafters 23 is an electric motor 32 whose shaft carries a beveled gear wheel 33 meshing with the beveled gear wheel 31. It will be obvious, therefore, that when this motor is energized

it will cause the roof structure to revolve around the central supporting pipe 13.

Current may be supplied to the motor through the wires 34, these wires being connected to rings 35 traveling over rollers 36. If one side of the motor be grounded, it is sufficient that there be one ring 35 and one roller 36, the roller 36 being connected to the source of current.

10 Carried by the rafters is the roof 37 which may be formed of metal, wood or of any desired material, this roof being formed with a plurality of facets so that each flat face of the roof may contain advertising matter.

15 The roof may have any desired form, but we have shown a roof which extends upward, then inward, and then upward, but do not wish to be limited to that. The upper end of the roof terminates in a finial 38 which sur-

20 rounds the terminal pipe 14 and rotates thereon, there being suitable means provided for preventing leakage at this point.

It will be seen that a structure of this kind is particularly effective as a stand for selling

25 candy, cold drinks, tobaccos, etc., and that by reason of the revolving top it will attract the attention of passersby. The revolving top may be painted in panels of different colors and may contain advertising matter,

30 as before stated, and be revolved at any desired rate of speed. The shutters not only close up the booth or stand when desired but, projecting out as they do from the space between each pair of posts, constitute awnings

35 protecting the person standing at the booth or stand from the sun or rain.

While we have illustrated a construction which we believe to be particularly effective, we do not wish to be limited to this as minor 40 changes might be made without departing from the spirit of the invention.

As shown in Figure 5, the central post or mast 12 extends a considerable distance above the top and carries upon it electric lights, 45 but it will be understood that these electric lights or others may be mounted upon the mast 12 or post below the top. It will likewise be understood that electric lights might be carried upon the revolving top or roof and 50 that these would add very much to the attractiveness of the building at night.

It will also be understood that the motor 32 might be disposed in any place within the building and be operatively connected to the 55 gear 31 to drive the rotatable top and that we do not wish to be limited to the location of the motor exactly as shown in Figure 3.

We claim:—

1. A building of the character described 60 comprising a circular roof structure, a vertically disposed supporting frame, means for rotatably mounting said roof on said frame, a stationary upright, and a motor mounted on the roof and engaging said upright where- 65 by to rotate the roof thereabout.

2. A building of the character described comprising a dome shaped roof structure, a vertically disposed supporting frame, a circular track, means for mounting the circular track in spaced relation to the upper end of the frame, roller means carried by the roof and engaging the track, an axially disposed upright, and means carried by the roof structure and engaging the upright whereby to 70 rotate the roof thereabout.

3. A building of the character described comprising a dome shaped roof structure, a supporting frame, a circular track upstanding from the frame, roller means dependingly secured to the dome and engaging said track whereby to permit the dome to rotate horizontally upon said frame, a vertically disposed mast, a gear secured to said mast, a motor secured to said dome and having gear connection with the gear on said mast whereby to permit the motor to rotate about said mast, and means mounted on the dome and engaging said mast whereby to transmit electrical energy to said motor. 75

4. A building of the character described comprising a dome shaped roof structure, a vertically disposed supporting frame, a circular track mounted on the frame, a plurality of brackets secured to the frame and engaging the track whereby to dispose the track in spaced relation to the frame, a plurality of brackets dependingly secured to the dome, a pair of rollers secured to each of said dome brackets, said rollers being adapted to engage said circular track at diametrically opposed points whereby to permit circular movement of the dome and coercively prevent removal of the dome from the track. 80

In testimony whereof we hereunto affix our signatures.

CHARLES T. RICE.
CHARLES E. CHILDS.
